UNITED STATES PATENT OFFICE.

GEORGE M. ASK, OF SAN JOSE, CALIFORNIA.

WATER ELEVATOR.

Application filed August 11, 1927. Serial No. 212,250.

This invention relates particularly to a means for raising water from a stream or other body of water through the operation of one or more windmills or other power plants positioned at a distance therefrom.

It is one object of the invention to provide a simple and economical mechanism of the character indicated that can be easily and efficiently operated by one or more small windmills or other suitable power plant located at any desired distance therefrom.

It is another object of the invention to provide mechanism of the character indicated wherein the power applied by the windmills may be regulated as desired at a point adjacent the elevating buckets.

In the drawing:

Figure 1 is a side elevation of the water elevator including its connections to the windmills.

Figure 2 is a side elevation, greatly enlarged, of a portion of the bucket operating mechanism.

Figure 3 is a plan view of the structure shown in Figure 2.

Figure 4 is a perspective illustration of a portion of the cable operating mechanism including the adjusting means.

Figure 5 is a fragmentary perspective illustration of one chain carrying sprocket.

Figure 6 is an enlarged detail of a portion of the power transmitting mechanism.

Referring now more particularly to the drawing, I show at 1 a framework constructed in any suitable manner to be fixedly positioned over a body of water and to extend a distance thereabove as shown.

On the frame 1 are mounted two parallel shafts as 2 and 3, these shafts being spaced a distance apart and one shaft as 3 being of somewhat higher elevation than the other.

On the shaft 2 are mounted two spaced sprocket wheels as 4—4, rotating with the shaft and having uniformly spaced peripheral notches formed therein as at 5.

On shaft 3 are mounted spaced sprocket wheels as 6—6 similar to sprockets 4 and provided with notches 7, and also radially arranged arms 8 mounted thereon. On this shaft are also mounted a pair of pulleys as 9 and 10, these pulleys being independently revoluble on the shaft and having dog and ratchet connections therewith as indicated at 11 and 12 respectively.

At 13 is shown an endless chain in which the links are connected by pins 14 extending

laterally therefrom on both sides to engage the notches 5 and 7 whereby the chain may be caused to travel in a vertical plane over the two sprockets, its upper portion between the two sprockets being on an incline as shown. Every other link in this chain carries a bucket 15 which fills on its upward movement, and empties into a trough 16 on the inclined portion of its path of travel. The arms 8 serve to engage the sides of the chain as they approach the first sprocket 3 and guide the pins 14 into the notches 5 and 7.

A third pulley 17 is mounted on the frame in a horizontal plane, spaced a distance from the pulleys 9 and 10, its axis lying in a vertical plane passing midway between the two pulleys as shown. A cable 18 is passed over the pulley 9 and around the same making one complete turn, thence around the pulley 17, and thence over the pulley 10 and completely around the same. The result of this construction and arrangement is that when one end of the cable 18 is pulled as indicated by the arrow 19 the pulley 9 is operated to rotate the shaft 3 and operate the buckets while the pulley 10 is rotated backwardly. When the other end of the cable is pulled as indicated by the arrow 20 the pulley 10 is operated to rotate the shaft 3 and operate the buckets while the pulley 9 is rotated backwardly.

Mounted on a frame 21 positioned on the ground a distance from frame 1 and in alignment with the pulleys 9 and 10 is an overbalanced rocking member 22. In the present case this member is shown as a triangle with its apex overlying the pivot 23 and on the side opposite to the frame 1. Its base is likewise angularly positioned and has a guide slot 24 formed therein. In the slot 24 and equally spaced on opposite sides of the pivot pin or shaft 23 are shoes 25 and 26, and adjacent each end of the slot are mounted pulleys 27 and 28. One end of the cable 18 is connected to one shoe as 25 at 29, and the other end is connected to the shoe 26 as at 30. A cable 31 is shown connected to shoe 25 at 32 and passing around the pulley 27 from below, thence around the pivot shaft 23 from above and back to the shoe 25 at 33. A cable 34 is shown connected to shoe 26 at 36 and passing under the pulley 28 and over the same and thence under and around the shaft 23 and back to the shoe 26 at 35. By means of this construction the length of the pull of the triangle when rocked, that is the pull upon the cable 18 in either direction, may be

varied by turning the shaft 23. Turning it in the direction indicated by the arrow will draw the shoes 26-25 toward each other and consequently shorten the pull on cable 18, and turning it in the opposite direction will move the shoes away from each other and lengthen the pull.

A rocking movement of the triangle in one direction is effected by means of a cable 36^a connected to its lower corner as 37 and to a windmill as 38 through the medium of any suitable eccentric connection not shown. The operation of the windmill pulls upon the triangle and raises its apex while the overbalanced arrangement of the triangle rocks it in the opposite direction when the pull on the cable is released.

If the windmill is located at some considerable distance from the triangle the efficiency of the pull is maintained without increasing the size of the cable by passing it over a pulley 39 on a suitable support 40 to the lower end of a rod 41 pivotally mounted as at 42, thence to a similarly mounted rod 43 pivoted at a point adjacent its upper end as 44 and continued from the lower end of the rod as 45 to another structure of the same kind or to the triangle as described. If several small windmills are to be used to operate the same cable they may be connected thereto at a given point as 46, additional leads to other windmills being indicated at 47.

It may now be seen that the cable 36^a may be operated by one or more windmills to rock the triangle 22 in one direction, thereby operating the buckets to raise water, and the overbalancing of the member 22 used to operate the triangle in the opposite direction, this movement also being utilized to operate the buckets to raise water.

It is to be understood, of course, that while I have herein shown and described but one specific embodiment of the invention, changes in form, construction and method of assembly

and operation may be made within the scope 45 of the appended claims.

I claim:

1. A water elevator comprising an endless chain having water buckets mounted thereon and revolvably mounted to travel in a vertical plane, a rocker arm mounted a distance therefrom, a cable connected to the arm at equal distances from its pivotal point, and adjustable relative to said pivotal point, gravity actuated means mounted on the arm to move 55 the same in one direction, power actuated means connected to the arm to move the same in the opposite direction, and cable operated mechanism operatively connected to the chain to rotate the same in one direction. 60

2. A water elevator comprising an endless chain having water buckets mounted thereon and revolvably mounted to travel in a vertical plane, a rocker arm mounted a distance therefrom, a cable connected to the arm at equal distances from its pivotal point, alternately acting power and gravity actuated means connected to the arm on opposite sides of its pivotal point, and cable operated mechanism operatively connected to the chain to rotate 70 the same in one direction. 65

3. A water elevator comprising an endless chain having water buckets mounted thereon and revolvably mounted to travel in a vertical plane, a rocker arm mounted a distance therefrom, a cable connected to the arm at equal distances from its pivotal point, cable operated mechanism operatively connected to the chain to rotate the same in one direction, a cable connected to the arm to actuate the same 75 in one direction and operating mechanism connected to the cable, a support mounted adjacent the last mentioned cable intermediate its length, and a swingable bar mounted on said support and inserted in the 80 length of the cable. 85
